UNITED STATES PATENT OFFICE.

WILLIAM B. DRAPER, OF CAMBRIDGE, ASSIGNOR OF ONE-HALF TO WILLIAM N. TODD, OF MELROSE, MASSACHUSETTS.

BUCKLE.

SPECIFICATION forming part of Letters Patent No. 504,867, dated September 12, 1893.

Application filed March 18, 1893. Serial No. 466,648. (No model.)

To all whom it may concern:

Be it known that I, WILLIAM B. DRAPER, of Cambridge, county of Middlesex, State of Massachusetts, have invented an Improvement in 5 Buckles, of which the following description, in connection with the accompanying drawings, is a specification, like letters and figures on the drawings representing like parts.

This invention has for its object to improve 10 and simplify the construction of buckles, and my invention consists in certain details of construction to be hereinafter pointed out in the claim at the end of this specification.

Figure 1, shows a front view of a buckle embodying this invention, a short piece of webbing being in engagement therewith; Fig. 2, a rear side view of the buckle with the webbing removed; Fig. 3, an edge view of the buckle shown in Fig. 2, with the upper part 20 turned to one side as it will be when the webbing is disengaged; Fig. 4, an edge view of the buckle and webbing shown in Fig. 1.

The buckle comprises essentially an upper and a lower part. The upper part is herein 25 shown as made of wire, bent to present a horizontal cross bar *a*, and a cross bar *b*, in parallelism therewith, and a central finger piece *c* rising from the cross bar *b*. The bars *a*, *b*, are located close together, the space between 30 being sufficient to permit free passage of the webbing *d*, and the finger piece is bent at an angle of say forty five degrees, with relation to the cross bar *b*, so that when said finger piece is in its vertical position, the bars *a*, *b*, 35 will occupy a position at an angle of about forty-five degrees with relation thereto, as best shown in Fig. 4. The lower part consists of a flat plate *f* having means at the lower end to which the suspender ends may 40 be attached, two slots 2, 3, being herein represented for said suspender ends. The upper end of the plate *f* is formed to loosely embrace the cross bar *a*, so that said upper and lower parts may be thus loosely connected together.

The upper end of the plate *f*, has formed upon 45 its rear side opposite the cross bar *a*, several teeth or projections 4, extending substantially at right angles with relation to the plate as shown in Fig. 4, and made nearly as long as the width of the space between the cross bars 50 *a*, and *b*. The webbing *d* passes down through the space between the cross bars *a* and *b*, over said teeth or projections as represented by dotted lines Fig. 3, so that the finger piece *c*, will be upon one side of the web and the plate 55 *f* upon the other, and then by turning the finger piece up into its vertical position, the cross bar *b* will pass over the teeth or projections, pressing the web into engagement therewith, and there hold it as represented in Fig. 60 4. To release the web the finger piece will be turned again into or toward its horizontal position, as shown in Fig. 3.

The buckle thus described is simple, easily operated, thin, presents a smooth exterior, 65 and may be cheaply manufactured, and presents on the face but a single wire.

I claim—

A buckle, the upper part consisting of the parallel cross bars *a*, *b*, with a narrow space 70 between them adapted to receive the web and a finger piece *c*, rigidly attached to said upper part arranged in a plane of substantially forty five degrees, with relation to the said bars, and the lower part consisting of the plate 75 *f*, the upper end of which loosely embraces the cross bar *a*, and has rearwardly projecting teeth 4, which co-operate with the cross bar *b*, to hold the material, substantially as described. 80

In testimony whereof I have signed my name to this specification in the presence of two subscribing witnesses.

WILLIAM B. DRAPER.

Witnesses:
